VALVE LIFT CONTROL DEVICE FOR FUEL INJECTING VALVES

Original Filed March 26, 1927

UNITED STATES PATENT OFFICE

JOSEPH C. GROFF, OF ALLENTOWN, PENNSYLVANIA

VALVE-LIFT-CONTROL DEVICE FOR FUEL-INJECTING VALVES

Original application filed March 26, 1927, Serial No. 178,537. Divided and this application filed March 27, 1928. Serial No. 265,092.

The present invention relates to fuel-injecting valves for internal combustion engines of the fuel injection type and more particularly to improvements in devices of this character which are adapted to effect airless injection of the fuel and which are adapted to function automatically without mechanical operating means other than a remotely located fuel supply pump.

10 This application constitutes a division of my co-pending application, Serial Number 178,537 filed March 26, 1927.

Previous devices of this character, particularly those employing a "needle" valve 15 of the outwardly (from the combustion chamber) opening type and which is adapted to be raised from its seat into its open position by the pressure action of the fuel upon exposed portions of its lateral section, have experienced certain objectionable characteristics.

For example, with such previous devices extreme difficulty has been experienced in satisfactorily eliminating the objectionable 25 feature of valve dribble. Previous attempts to correct one of the principal causes for the occurrence of such valve dribble, namely, excessive extent of lift of the valve from off its seat, have been accompanied by certain objectionable results.

Thus, with such previous attempts to restrict the extent of the lift of self-opening spring loaded injecting valves, difficulty has been experienced in preventing the springs 35 from fracturing themselves after varying and uncertain periods of operation. Also, such previous devices for restricting the lift of fuel injecting valves of the automatic needle type have been objectionably noisy in 40 operation.

The present invention has for its objects the provision of novel means for restricting the extent of lift of a fuel injecting valve of the needle and automatic airless injection 45 type.

Further objects of the present invention reside in the provision of means for providing a film or cushion of oil to receive the impact of the valve member as its extent of lift 50 is restricted.

A further object of the present invention resides in the provision of novel means whereby the extent of the restriction of the valve lift of an automatic needle type fuel injecting valve may be substantially independent and unaffected by the unavoidable and variable changes in temperature of the valve parts.

A further object of the present invention resides in the provision of novel manually manipulative means for adjusting the extent of restriction of the valve lift.

Further and more detailed objects and advantages of the present invention will be hereinafter pointed out in the accompanying specification and claims, and shown in the drawings which, by way of illustration, show what I now consider preferred embodiments of my invention.

In the drawings:
The figure shows a longitudinal cross sectional view of my improved fuel injecting device.

According to the present invention, the stemlike portion 148 of an outwardly (away from the combustion space 103 as formed by the concave surface of wall structure 102) opening fuel-injecting valve 134, which is of the so-called needle non-return type, is adapted to reciprocate within any suitable stationary, though axially adjustable, abutting and restraining member such as sleeve-like member 101. Valve 134 is held tightly against its seat 92 in its closed position (as shown in Fig. 1) by any suitable means such as by the downward compressive effect of any suitable spring 91.

Preferably, said stem portion 148 is adapted to reciprocate inside of sleeve-like member 101 with a closely machined sliding fit to thus effect a fluid-tight sliding joint without using elastic packing means to prevent leakage of fuel oil therebetween. Similarly, leakage of liquid fuel past the outside portion of said sleeve member 101 is preferably prevented by its effecting a carefully machined sliding fit with any suitable bored-out portion of body member 98.

Sleeve member 101 is adapted to be held rigid against axial movement with respect

to body member 98 by any suitable means such as the screw-threaded connection 132. I prefer to locate the point of restraining connection 132 as close to the valve seat 92 as 5 may be permissible. With this novel construction, whereby the respective points of support and of abutting contact of the various interacting valve parts 92, 132, 133 and 134 are substantially axially-coincident, the 10 objectionable effects of differential expansion caused by unavoidable changes and differences in temperature of said interacting valve parts, which have heretofore caused objectionable variation in the axial working clear- 15 ances between said parts, may be eliminated.

In operation, sleeve member 101 is preferably adjusted to have some definite predetermined axial position with respect to body member 98 and such adjustments may be effected by any suitable means such as by the manually-manipulative quadrant lever 99. Thus, circular movement of radial arm 99 acts to axially advance or retard sleeve member 101 in accordance with the pitch of 25 threaded connection 132. I prefer to screw sleeve member 101 down towardsthe valve seat 92 until the resultant axial clearance 131, between valve 134, when the latter is in its closed 30 position on seat 92, and the bottom annular end portion 133 of sleeve member 101, is comparatively small in extent.

Accordingly, the axial lift of valve 134 may be restricted to have any extremely small extent of travel, such as is indicated by 131, and 35 said extent of lift may be adjusted at will while the valve is in operation by merely changing the axial position of sleeve 101 as previously described.

Upon and by the initial supplying of liquid fuel to my injecting device, from any 40 suitable fuel supplying means not shown in the drawings, the liquid thereby supplied via pipe 29 and any suitable passage 136 acts as a pressure medium to exert an upward and 45 valve-opening force upon the aforementioned valve member 134. That is to say, such liquid pressure medium initially acts upward on an exposed lateral region of valve 134 which has a lateral effective area substan- 50 tially equivalent to the lateral area of stem 148 less the area of a circle the diameter of which is substantially the mean diameter of valve seat 92.

Subsequently however, with valve 134 once 55 initially raised off its seat 92 it is held open and against bottom end 133 of sleeve member 101 with an upward force determined by action of the pressure medium against an effective lateral section which is equivalent in area 60 to the lateral area of stem 148.

It should be understood, that a considerable pressure must be exerted upon the entrapped liquid fuel in order to inject necessarily fast moving jets 94 of fuel into the combustion space 103 via the small sized

70 spray nozzles 93 and in the short period of time available. In other words, supply pipe 29, passage 136 and the interior passage space just adjacent to the spray nozzles 93 are exposed to relatively high pressure action by the oil fuel during the period of its injection via nozzles 93, and it is this pressure which acts to open and maintain valve member 134 unseated during such injection.

I am fully aware that outwardly opening 75 spring-loaded needle type valves, which are automatically opened by pressure action from a remotely located fuel supplying pump, have been previously used for the purpose of effecting airless fuel injection. However, such previous devices have experienced considerable 80 objectionable operating difficulties and this has been largely due to their improper construction. For example, with such previous devices excessive smoking of the exhaust gases 85 has been experienced, there has been formed objectionable deposit of carbon in the combustion spaces and in and around the outside of the fuel spray nozzles. It should be understood that such objectionable performance is 90 principally caused by passage of a portion of the charge of injected fuel through said spray nozzles with insufficient velocity to properly atomize and remove the fuel from the region of said nozzles. Such improper 95 passage of the fuel through the spray nozzles is better known as "valve dribble".

Furthermore, such previous injection-valve devices have failed to provide means for properly controlling the opening and closing operations of the valve member such as 134. That is to say, previous attempts to restrict the extent of valve opening, which restriction of lift constitutes one of the most important 100 provisions to prevent the aforementioned objectionable valve-dribble effects, have been accompanied by uncertain performance and by erratic failure of the spring (such as 91) used to close and seat the valve (such as 134). Also, as previously mentioned, such previous 105 devices have been noisy in operation.

Referring to Fig. 1, it will be seen that I provide novel cushioning means for automatically protecting the various valve parts 133, 101 and 134 against the objectionable effects 110 heretofore experienced. Thus, the aforementioned initial supplying of fuel causes valve member 134 to move upwards with considerable 115 velocity until 134 abuts against annular seat 133 of sleeve 101. However, with my novel construction, whereby the interacting and abutting parts are at all times immersed in the liquid fuel, which necessarily fills the valve passages, a layer or cushion of such oil is always interposed between said abutting 120 parts. Thus, while effectively restricting the lift of valve 134, the construction of sleeve member 101 also prevents too sudden deceleration of said valve 134 and of spring 91 to thus 125 eliminate objectionable noise and to thus pre- 130

vent harmful vibratory effects being imparted to said spring 91.

The importance of so properly restricting the extent of lift of an automatic airless fuel injecting valve may be better understood by saying:

(a) That the fuel supply pump (not shown in the drawings) supplies fuel to the passages of the injection valve at a certain given rate (viz, at so and so many units of volume per unit of time).

(b) That the fuel, upon its initial delivery via passage 136, acts upon needle valve 134 in an upward direction to initially raise 134 from off its seat 92.

(c) That, upon such initial opening of said valve 134, the spray nozzles 93 are exposed to the pressure action of the entrapped fuel being delivered thereto and, naturally, injection of the fuel into combustion space 103 commences via said nozzles 93 upon and subsequent to said initial exposure.

(d) That the velocity of the fuel so initially injected is determined by, and therefore is not at its desired maximum value during, the opening movement of valve 134. That is to say, during the opening action of valve 134, a portion of the fuel so initially supplied by the pump must go to fill up the space created 30 by the upward receding movement of said valve 134.

(e) That, during such opening and upward receding movement of valve 134, which continues until the valve comes to rest against 35 restraining means such as annular seat 133, the velocity of passage of the fuel through spray nozzles is comparatively low. That is to say, the spray nozzles are initially subjected to a reduced fuel pressure during opening movement of valve 134, which pressure is substantially equivalent to the reduced pressure necessary to overcome the downward compressive force of spring 91 upon valve 40 134. This has to be else the valve 134 would not open automatically without use of excessive fuel pressures.

(f) That such reduced rate of spray nozzle velocity continues until the opening movement of valve 134 ceases, at which time the 50 entire desired rate of spray nozzle velocity is secured and continues up until substantially the instant that supplying of the fuel via pipe 29 ceases.

(g) That, upon such cessation of fuel supply via pipe 29, the fuel pressure in passage 55 136 drops somewhat abruptly.

(h) That, during and immediately subsequent to such cessation of fuel supply via pipe 29, fuel continues to pass through nozzles 93, 60 but with objectionably diminishing velocity, until spring 91 has finally forced valve 134 onto its seat 92. That is to say, such downwardly closing movement of valve 134 involves the displacement of a portion of the 65 liquid fuel in the passage-space adjacent to

seat 92 and the fuel so displaced can only escape by passing through nozzles 93.

Accordingly, provision of means, whereby the objectionable operating characteristics of previous devices of this character are eliminated, is considered to be novel.

It should be understood, of course, that my novel valve construction may be modified in its detail arrangement without departing from the broad scope of my invention. Thus, 75 for example, other and different known packing means may be employed to prevent leakage of the liquid fuel past the sliding joint between stem 148 and the inner portion of sleeve member 101 and/or past the 80 sliding joint between the outside surface of 101 and body member 98.

What I claim is:

1. A fuel-injecting valve device comprising a needle valve constructed and arranged to be lifted from its seat by the pressure action of the fuel which is to pass such valve, said device including a fuel supplying chamber which always contains a viscous fuel medium under maintained pressure, said valve 85 having a stem and head portion in combination with means for restricting the extent of valve lift, said means comprising a member surrounding the stem of said valve and having an end portion constituting an abutment 90 to engage said valve head and restrict the valve lifting movement, said end portion being axially adjacent the head portion of the valve, said end and head portion extending into said fuel supplying chamber, the aforesaid member which surrounds the valve stem being mounted for relative axial adjustment 95 with respect to the valve for the purpose described.

2. In a fuel-injecting device of the character described and having a body member in communication with fuel-supply and fuel-injecting passages, a fuel valve member and a valve seat therefor interposed between said supply and injecting passages, said valve member having a stem portion adapted to effect a sliding joint within a bored-out portion of said body member, said body member having a stationary but axially adjustable interior annular portion co-axially disposed with respect to said stem portion and facing said valve seat and adapted to restrictively engage an abutting projection carried by said valve member and located within an interior fuel supply passage of said body member adjacent to said valve seat for the purpose of restricting the extent of axial movement of 115 said valve member with respect to said valve seat.

3. In a fuel-injecting device of the character described and having a body member in communication with fuel-supply and fuel-injecting passages, a fuel valve member and a valve seat therefor interposed between said supply and injecting passages, and means as- 120 125 130

sociated therewith for restricting the extent of lift of said valve, said means comprising a stationary sleeve-like member co-axially disposed with respect to, and surrounding, a stemlike portion of said valve member and effecting a sliding joint therebetween, said sleeve-like member having its interior annularly-shaped end portion facing, and located within an interior fuel supply passage of said body member adjacent to, said valve seat and adapted to restrictively engage an abutting projection carried by said valve for the purposes set forth the aforesaid sleeve-like member having a threaded connection with the body member so that the relative position of the sleeve-like member may be adjusted with respect to the body member and to the valve so that the valve lift may be adjusted while the engine is in operation.

10   20   In testimony whereof I hereto affix my signature.

JOSEPH C. GROFF.
